UNITED STATES PATENT OFFICE.

JOHN H. JOHNSON, OF OMAHA, NEBRASKA.

ATTACHMENT FOR STEEL SQUARES AND THE LIKE.

1,225,132.

Specification of Letters Patent.

Patented May 8, 1917.

Application filed May 2, 1916. Serial No. 94,976.

To all whom it may concern:

Be it known that I, JOHN H. JOHNSON, a citizen of the United States, residing at Omaha, in the county of Douglas and State 5 of Nebraska, have invented a new and useful Attachment for Steel Squares and the like, and have described the same in the following specification, illustrated by the accompanying drawings.

10 My invention relates to that class of adjustable and removable attachments which are commonly applied to steel squares, and span the interior angles of steel squares, used by carpenters in building and remodeling operations, for laying out their work, and for determining and transferring to and from the rafters, braces and other material parts and elements of buildings and other structures, the requisite or desired lines, bevels, pitches, angles, cuts, joints, measurements and correlative positions. It is the 15 object of the invention to point out in terms of rise and run on the arms of the common steel square the grade, or pitch, of any existing inclined edge, surface or line to which the square may be applied; by means of such a square, supplied with this attachment, to set at any required angle with a given line any straight piece of building material 20 to which the square is applied; to obviate all need of having a spirit level, or its equivalent, permanently incorporated in the square, or in either of its arms; to render the device attachable to the inner edges of the 25 arms of the square, while the outer edges of the same remain free for unobstructed contact with the work or structure to which the square is applied; to render the attachment operatively applicable to the square, and attachable thereto, without drilling or otherwise perforating the square itself, or either of its arms; at the same time to adapt the attachment, when separated from the square, and fastened to a straight-edge, to produce 30 a combination with the straight-edge a complete and convenient carpenter's level; and in general to increase the usefulness of the typical steel square. To accomplish this object, I incorporate in my improved attachment, as parts thereof, a bar having longitudinally alined sections which are united by a sliding joint, a spirit level which is carried by one of the sections, and junction members, which are carried by the sections 35 respectively, and are adapted to engage the arms of the square.

In the accompanying drawings, illustrating the best manner in which I have contemplated applying the principles of the invention, Figure 1 is a side elevation of an attachment of the specified class, which is constructed in accordance with these principles and operatively applied to a steel square. Fig. 2 is a side elevation of the same attachment, differently adjusted and operatively 60 applied to one arm of the square. Fig. 3 is a longitudinal central section of the same attachment differently adjusted. Fig. 4 is a cross section of the same on the section line 4—4 in Fig. 3. Fig. 5 is a side elevation of 65 the device and its associated steel square, operatively applied to a roof rafter for the purpose of determining its pitch.

In these drawings the numerals 12 and 13 denote respectively the blade and the 70 tongue of a typical rectangular steel square, having, marginally marked thereon, the usual graduated scales indicated by the numerals 1 to 11 inclusive. The illustrated specimen of my invention, variously applied 75 to this square, comprises the axially alined tubular sections 14 and 15, and is variable in length by the telescoping of these sections. Each section, being open at its telescoping 80 end, is closed at its opposite end by deformatively pressing its opposite semicircular peripheral walls together and thereby forming a flat terminal ear 16, curvilinear in outline, wider from side to side than the body 85 of the tube, and co-axial therewith. A pair 90 of guides 17, spaced apart by the ear, and having the index fingers 18 extending beyond its margin in parallel planes, are adjustably pivoted thereto on the screw bolt 19, which passes centrally through the ear 95 and is provided with the thumbsnut 20. The outer tube 14 carries the spirit level 21 and has an air-hole 22.

Operatively to adapt either arm of the square to be used as a level, affix the attachment thereto, in parallelism therewith as in Fig. 2, by placing the ears 16 in edgewise contact with the arm, turn the index fingers to vertical overlapping positions on the opposite sides of the arm, and clamp them 100 thereto by turning the thumbsnuts. To convert a straight edge into a level, affix the described attachment thereto in the same manner. To determine operatively the pitch of a given line, as for example the 105 pitch of the rafter 23, place one arm of the square along the rafter, as in Fig. 5,

affix the attachment in a horizontal position, subtending the angle of the square, by placing the ears 16 in edgewise contact with the arms of the square respectively, as shown, and by turning the pairs of fingers 18 pivotally to alined positions overlapping the arms of the square. The rise and run of the rafter may then be read at the points of intersection of the fingers with the arms 10 13 and 12 respectively. Thus the pitch read on Fig. 1 is rise three and three-quarters, and run five and one-half; which may be taken as inches, feet, or other units of long measure. In this way the square and the 15 attachment together can be used as a slide rule on which the rise of the inclined surface or line can be read, when the run is given; and the run, when the rise is given.

I claim as my invention—

- 20 1. An attachment for steel squares and the like, comprising a bar having two alined sections united by a telescoping engagement; a spirit level mounted on one of the sections; and terminal junction members, 25 pivoted to the ends of the bar respectively, and adapted to engage the limbs of the square.

2. An attachment of the specified class, comprising two telescoping tubes; a level mounted on one of the tubes in parallelism 30 therewith; and junction members carried by the tubes respectively for engagement with a steel square or the like.

3. An attachment of the specified class, comprising two alined sections united by a 35 telescoping engagement; a level carried by one of the sections; and terminal junction members pivoted to the sections respectively.

4. An attachment of the specified class, comprising a bar of variable length; a spirit 40 level carried thereby; and terminal junction members pivoted to the bar and having index fingers.

5. An attachment of the specified class, comprising a bar having a level carried 45 thereby; and terminal clamps pivoted to the bar and provided with index fingers.

6. An attachment of the specified class, comprising a bar having a level carried thereby; index fingers pivotally mounted on 50 the ends of the bar, and means for clamping the fingers in different positions of pivotal adjustment.

JOHN H. JOHNSON.
